UNITED STATES PATENT OFFICE.

JAMES G. HALLAS, OF WATERBURY, CONNECTICUT, ASSIGNOR TO THE BENEDICT & BURNHAM MANUFACTURING COMPANY, OF SAME PLACE.

DRAWER-PULL.

SPECIFICATION forming part of Letters Patent No. 289,251, dated November 27, 1883.

Application filed September 24, 1883. (No model.)

To all whom it may concern:

Be it known that I, JAMES G. HALLAS, of Waterbury, in the county of New Haven and State of Connecticut, have invented a new Improvement in Drawer-Pulls; and I do hereby declare the following, when taken in connection with accompanying drawings and the letters of reference marked thereon, to be a full, clear, and exact description of the same, and which said drawings constitute part of this specification, and represent, in—

Figure, 1 a front view; Fig. 2, a side view; Fig. 3, a vertical central section; Fig. 4, the parts of the handle detached.

15 This invention relates to an improvement in that class of drawer-pulls in which a handle is hinged to a socket, so as to turn down and in its normal condition hang vertically, but so that when in use the pull or handle is turned 20 upward into a horizontal plane, and particularly to that class which are made from sheet metal, the object of the invention being to simplify the construction of the pull; and it 25 consists in the construction, as hereinafter described, and more particularly recited in the claim.

A represents the rose, which is applied directly to the drawer-front, and may be of any desirable pattern; B, the socket; C, the screw; 30 D, the bar of the handle; E, the shank which is hinged in the socket.

The handle D is a horizontal bar, made from tubing, closed at each end, as indicated in broken lines, Fig. 1. E is the shank, made 35 from tubing, its lower portion of a diameter corresponding substantially to the diameter of the bar D, and so as to set upon and fit the surface of the bar D, as seen in Figs. 3 and 4. The upper end of the shank E is constructed

to enter the recess in the outer end of the 40 socket, and through that end of the shank, and diametrically through the socket, the pintle f is introduced, in the usual manner for hinging drawer-pulls to the socket. The bar is secured to the shank by a headed screw, I, passed diametrically through the bar, holes h, made 45 therein for that purpose, and screwed into the upper end of the socket, that end of the socket being tapped for the purpose, as at i. The bar is set in position against the lower end of 50 the shank, then the screw introduced and turned to bring its head hard against the under side of the bar, as seen in Fig. 3. This construction gives to the pull the appearance 55 of a fine cast-metal T-shaped handle, and at a comparatively small cost, for the reason that the cast-metal T-shaped pull is necessarily finished by mechanical operations which are 60 in themselves expensive, whereas by making the bar and socket from sheet metal drawn to shape the surface is finished without such expensive mechanical operations.

The screw or shank C, it will be understood, is made male or female, according to the character of the fastening, in the usual manner for 65 the shank or screw of drawer-pulls.

I claim—

In a drawer-pull, the combination of a tubular bar, D, the shank E, one end fitted to the surface of the bar, the other constructed 70 for attachment to the socket, and the screw I through said bar into the socket, substantially as described.

JAMES G. HALLAS.
